UNITED STATES PATENT OFFICE.

MARK ST. CLAIR ELLIS, OF THE UNITED STATES NAVY.

SELF-SCORING TARGET.

1,041,258.

Specification of Letters Patent.

Patented Oct. 15, 1912.

Application filed January 19, 1911. Serial No. 603,589.

To all whom it may concern:

Be it known that I, MARK ST. CLAIR ELLIS, a citizen of the United States and a resident of Philadelphia, in the county of 5 Philadelphia and State of Pennsylvania, lieutenant-commander of the United States Navy, stationed at the United States Naval Magazine, Mare Island, California, have invented certain new and useful Improvements 10 in Self-Scoring Targets; and I do hereby declare the following to be a full, clear, and exact description of the invention, such as will enable others skilled in the art to which it appertains to make and use 15 the same.

This invention relates to targets of the electro-mechanical type, designed particularly for use in training boy scouts to shoot; but as the principles involved in its 20 construction may be applied to any form of the United States Army or Navy regulation target, the right to use it for the same is hereby claimed.

It embodies the manifest advantages of 25 self-marking targets over targets where the marking is done by hand.

In the drawing attached hereto and forming part of the specifications, Figure 1 shows a front elevational view of the target, 30 as a whole, assembled and ready for use. Fig. 2 shows a vertical central sectional view; Fig. 3 shows a detail view of the contact maker, and Fig. 4 shows a detail view of the method of securing the sections of 35 armor plate to the supporting bulkhead.

Referring to the drawing, I describe the target as applied to a miniature target having dimensions of two feet wide, by three feet high.

40 The annunciator represented at "A" is of commercial type, and has its front face made to represent a miniature of the target face.

The battery shown at "B" is preferably 45 of the storage battery type, and is connected in circuit in the electric cable "C".

The cable "C" leads from the annunciator "A" at the firing point to the back of the bulkhead "D".

50 The target mechanism is securely attached to the base "F," which may be made of wood or channel bar iron, as desired.

The paper or aiming target "H" is placed in front of the bulkhead "D" and held in

the framework "G". The reason for using 55 this paper target "H", is that it is cheaper and less trouble to use a paper target than it is to paint the faces of the designating plates hereinafter described. The holding bulkhead "D" is made of a strong steel 60 plate slightly smaller than the dimensions of the paper target. Its function is to provide a holder for the designating plates "P". Attached to "D" by the through bolts 11, are the holding brackets 8, and 65 between the brackets 8 and the bulkhead "D" is the buffer 7, made of rubber or other resilient substance, and attached to 8 by the through bolts 12 are the designating plates "P." There are as many of the designating 70 plates "P" as the requirements of definition demand. The designating plates "P" are made of hard steel or armor plate. I have found a suitable steel which will stand indefinitely the impact of the bullet of the new 75 Springfield rifle at 200 yards, and yet this armor plate is only $\frac{1}{2}$ " thick. The function of the rubber buffer 7 is to absorb the impact of the bullet when the plate "P" is struck and to prevent vibration from being 80 set up in the bulkhead "D", which would defeat the purposes of accurate scoring.

In Fig. 3 I show details of an improved contact making device. The spring 9 holds the ball "K" against the rear face of the 85 designating plates. The designating plates and the spring 9 are wired electrically to the common return. The spring 10 inside of the spring 9 and insulated therefrom is wired to its own section of the annunciator. 90 Secured to the spring 10 is the cup "L", against which "K" impinges and closes the electrical circuit when "P" is struck by the bullet. I provide means of adjusting the spring 10 by the pad eyes 13, and the flexible wire 14.

Having thus described the various parts of my invention, the action of the target under fire is as follows: The firer stands near the annunciator "A", and aiming at 100 the target "H", strikes, let us assume, the number 4 area of the target. In the paper screen shown, the center, or number 5 is given the count of five, the next ring the count of four, the next the count of three, 105 and all outside thereof the count of two. The bullet striking the number 4 area of the paper target passes therethrough, and

impinges upon the number 4 designating plate directly in rear thereof. The bullet breaks to pieces against the front face of the hard steel plate, dissipating in small 5 fragments, but in so doing it imparts its energy to the designating plate "P", and the shock is absorbed by the resilient buffer 7. At the same time the enlarged point "K" of the spring 9 rebounds from the 10 plate "P", touches the contact making cup "L" held by the spring 10. This makes a prolonged contact, by the ball tip pressing against the cup attached to the inner spring and following it up to compression and release giving the electric current time to 15 overcome the resistance in the wire of the cable "C", and to actuate an appropriate portion of the annunciator "A". When the energy of the shock is dissipated, the contact 20 maker and the plates resume their normal position. The action above described as taking place when a section of the number 4 is struck, is the same as that which occurs when any other section is struck.

25 I do not limit myself to the exact construction as shown in the accompanying details, as a number of minor changes are foreseen which come within the scope of my invention.

What I claim as new, and desire to secure 30 by Letters Patent of the United States is:

In self scoring targets the combination of 35 designating plates, brackets for supporting said plates, a holding bulkhead on which said brackets are mounted, with rubber buffers located between said brackets and said bulkhead as resilient shock absorbers to take up the blow of the bullet and prevent vibration in the designating members not struck, an annunciator and circuit 40 closers consisting of helical springs with weighted tips mounted on said buffers and normally resting against the designating plates, other springs carrying cups and mounted on said buffers within said first 45 named springs, said weighted tips adapted to leave said plates when the latter are struck and to recoil and touch the cups sustained by said inner springs thus closing an electric circuit, and actuating an annunciator through suitable cable and batteries, substantially as shown and described.

In witness whereof, I hereunto set my hand.

MARK ST. CLAIR ELLIS.
